UNITED STATES PATENT OFFICE.

ULYSSE LAPLACE, OF NEW ORLEANS, LOUISIANA.

CENTRIFUGAL FILTERING-MACHINE.

SPECIFICATION forming part of Letters Patent No. 650,402, dated May 29, 1900.

Application filed July 27, 1899. Serial No. 725,317. (No model.)

To all whom it may concern:

Be it known that I, ULYSSE LAPLACE, a citizen of the United States, residing at New Orleans, in the parish of Orleans and State 5 of Louisiana, have invented new and useful Improvements in Centrifugal Filtering-Machines, of which the following is a specification.

My invention relates to centrifugal machines, and contemplates the provision of a centrifugal filtering-machine which, while very simple and inexpensive, is calculated to expeditiously filter liquids of various kinds.

The invention will be fully understood from 15 the following description and claims when taken in conjunction with the annexed drawings, in which—

Figure 1 is a diametrical section of a centrifugal machine embodying a drum constructed in accordance with my invention. Fig. 2 is a broken perspective view of the annular filter-body of the drum. Fig. 3 is a circular filter-stone which is permeable to water and is designed to form part of the drum when 25 water is to be filtered.

Referring by letter to the said drawings, and more particularly to Figs. 1 and 2 thereof, A is the casing of a centrifugal machine, B a shaft journaled in the bottom wall of the same, 30 and C a drum fixed on the shaft to be rapidly revolved by power applied to the latter. G indicates the perforated cylinder, which is usually arranged in the casing, and H the wire-gauze, arranged on the inner side of said cylinder. The drum in the preferred embodiment of the invention is made up of a base a, fixed on the shaft B and having an upwardly-disposed flange b, a crown or crown-annulus c, having a depending circular flange 35 d, an adjustable connection which is preferably formed by rods e, connected to the base a and loosely extended through apertures f in the crown-annulus c, and nuts mounted on the upper threaded ends of the rods, and 40 an annular and rigid filter-body D of a diameter to snugly fit within the flanges b d of the base and crown-annulus.

The filter-body D comprises a receptacle h, of sheet-brass, copper, or other suitable material, having inner and outer foraminated walls i j and a preferably imperforate annular bottom wall k and a filling l of some suit-

able filtering material, such as charcoal. Said filter-body D is placed between the base a and crown-annulus c and within the circular 55 flanges of the same and is secured in such position by turning the nuts g down on the rods e to the extent necessary.

E' are annular gaskets, of rubber or other suitable material, which are interposed between the lower and upper ends of the filter-body D and the base a and crown-annulus, respectively. These gaskets serve to preclude the escape of liquid between the ends of the filter-body D and the base a and crown-annulus c and compel all of the liquid which leaves the drum to pass through the said filter-body D.

As illustrated in Fig. 1, the machine is designed more especially for filtering oil, wine, 70 and like liquids, the liquid being placed in the drum and said drum being rapidly revolved by power applied to shaft B, so as to force the liquid through the filter-body D, and thereby effect a thorough separation of 75 sediment and foreign particles therefrom. The sediment and foreign particles in the liquid are caught and held in the filtering material, and hence it frequently becomes necessary in order to maintain the efficiency 80 of the machine to remove such filtering material and replace it with fresh material. The construction described admits of this being quickly and easily accomplished, it being simply necessary when the filtering material 85 is choked by sediment and impurities to remove the nuts g and crown-annulus c from the rods e and then lift the filter-body D as a whole out of the machine and dump the filtering material from the receptacle h. The 90 said receptacle h is then filled with fresh filtering material and the filter is replaced and secured between the base a and crown-annulus c, when the machine is again ready for use.

When it is desired to filter water, the filter-body D is removed from the machine and its place is taken by the rigid filter-body or filter-stone D', (shown in Fig. 3,) which is permeable to water. The said filter-body or filter-stone may be annular in form, like the filter-body D, or in the form of a circular vessel, as shown in Fig. 3. In the latter case the lower gasket E' is not essential, but is pref-

erably employed in order to lessen the liability of breakage when the filter-body or filter-stone is clamped between the base and crown-annulus.

5. Like the filter-body D the filter-body or filter-stone D' is susceptible of being readily removed, cleared of sediment, and replaced in the machine, and when it is employed the efficiency of the machine may be maintained 10 for an indefinite period without the employment of new materials.

It will be appreciated from the foregoing that both embodiments of my invention are very simple, inexpensive, and durable and 15 that when a conduit is arranged to continuously discharge liquid into the drum C no attendant is necessary. It will also be appreciated that because of the facility with which the filter-body may be removed, cleaned, and 20 replaced the machine need not be idle but a very short time, which is an important advantage.

I indicates a brake; which may comprise an arm J, hinged at its outer end to a lug K, 25 rising from the side of the casing and having its opposite or inner end provided with an under socket or seat L for the reception of a block M of suitable material such as leather, wood, or the like. This block or shoe may 30 be swung on its hinge-joint so as to be thrown outwardly when not in use, and when it is desired to stop the motion of the machine

after the power has been cut off the shoe is pressed by the hand or otherwise on the upper side of the annulus c.

Having thus described my invention, what I claim is—

1. The combination, in the drum of a centrifugal machine, of a base, a crown, a connection between said base and crown, and an annular filter-body interposed between the base and crown and removable therefrom; said filter-body comprising a receptacle made up of inner and outer foraminated walls and a bottom permanently connected to said inner and outer walls, and a filling of filtering material arranged therein, substantially as specified.

2. A filter-body, for use in the drums of centrifugal machines, comprising an annular receptacle made up of inner and outer foraminated walls, and a bottom permanently connected to said inner and outer walls, and a filling of filtering material arranged in said receptacle and removable therefrom, substantially as specified.

In testimony whereof I have hereunto set my hand in presence of two subscribing witnesses.

ULYSSE LAPLACE.
